Des. 196,806
Patented Nov. 5, 1963

196,806

CLOTHES WASHER OR SIMILAR ARTICLE

Lawrence R. Collins, Jefferson County, Ky., assignor to
General Electric Company, a corporation of New York

Filed Mar. 22, 1963, Ser. No. 74,091

Term of patent 14 years

(Cl. D49—1)

FIG.4

FIG.2

FIG.3

FIGURE 1 is a fragmentary front perspective view of a clothes washer embodying my new design;

FIGURE 2 is a cross-sectional view thereof taken on the lines 2—2 of FIGURE 1 in the direction of the arrows;

FIGURE 3 is a fragmentary cross-sectional view thereof taken on the lines 3—3 of FIGURE 1 in the direction of the arrows; and

FIGURE 4 is a side elevational view thereof.

The broken lines representative of the lower portion of the clothes washer have been omitted in FIGURE 1 for convenience of illustration.

The front, the back, and the side not shown of the clothes washer are substantially plain. The dominant

features of my invention for the clothes washer disclosed reside in the portions shown in full lines.

I claim:

The ornamental design for a clothes washer or similar article, substantially as shown and described.
